HARRY Y. NORWOOD, OF ROCHESTER, NEW YORK, ASSIGNOR TO TAYLOR INSTRUMENT COMPANIES, OF ROCHESTER, NEW YORK, A CORPORATION OF NEW YORK.

PRESSURE RESPONSIVE DIAPHRAGM.

Application filed January 18, 1922. Serial No. 530,202.

This invention relates to pressure responsive diaphragms of the variety employed for converting fluid pressure into mechanical motion, having as its chief object the provision of an efficient device of the above character provided with simple and practical means for effectively supporting the flexible surface or surfaces in an extreme or limiting position of expansion to prevent distortion or rupture of the same by subjection to excessive pressure. To these and other ends the invention resides in certain improvements and combinations of parts all as will hereinafter be more fully described, the novel features being pointed out in the claims at the end of the specification.

In the drawings:

Figure 1 is a central sectional view of a device embodying the present invention and illustrating the same at an initial step in manufacture;

Figure 2 is a similar view showing a further step with the diaphragms expanded by pressure;

Figure 3 is a similar view showing the device completed;

Similar reference numerals throughout the several views indicate the same parts.

The embodiment of the invention selected for the purposes of the present disclosure as best illustrating the principles involved comprises an expansible pressure responsive diaphragm of the so-called "wafer type," such as commonly employed, for example, in pressure and temperature measuring or regulating apparatus for converting fluid pressure into proportional mechanical movement. There are employed in the present instance a pair of opposing flexible diaphragms or walls 5 and 6, respectively, which are preferably formed of disks of resilient sheet metal concentrically corrugated as shown to provide for expansion by pressure admitted between the diaphragms. The latter are connected at their peripheries to complete a fluid tight receptacle by a flexible circumferential binding strip in the form of a rim or flange 7 spun over at its edges 8 to embrace outwardly projecting peripheral edges 9 of the diaphragms, these overlapping edges being preferably soldered to form a nonleakable receptacle. Diaphragm 5 has soldered or otherwise fixed at its center a reinforcing disk or boss 10 for engagement with a part 55 of the mechanical apparatus to be operated

by the device, as more fully appears hereafter. The other diaphragm 6 has a central opening, the edges of which embrace and are fitted against a shoulder 11 on a plug 12 one end of which extends between the diaphragms and is spun over as at 13 on the diaphragm 6 to secure the latter to the plug by a fluid tight connection. Plug 12 has a threaded reduced portion 14 engaging a correspondingly threaded socket or opening 65 in the end of a coupling member 15 which is externally threaded to provide for connection of the same with a conduit leading to the source of pressure. Plug 12 and coupling member 15 have registering channels 70 16 and 17, respectively, through which the pressure is transmitted between the diaphragms.

The present improvements are in this instance embodied in a diaphragm of the above type, although applicable, of course, to various other forms of diaphragm construction, and comprises means, generally speaking, for uniformly and effectively supporting substantially the entire surface of a diaphragm in an expanded position of the latter for preventing excessive movement and possible permanent distortion and injury of the diaphragm when subjected to pressures higher than those for which it is designed. 75 As the device with which the invention is combined in the present instance has opposing expansible surfaces, the supporting means comprises a pair of plates 18 and 19 disposed on opposite sides of the diaphragm 90 and supported on the comparatively rigid periphery of the same formed by the laterally projecting portions of the binding strip or flange 7. These plates are preferably constructed of metal having sufficient thickness 95 and strength to provide substantially rigid walls capable of resisting the outward pressure of the diaphragms. The plates are larger in diameter than the diaphragm so as to extend outwardly beyond the periphery 100 of the same and their projecting marginal portions are connected by tying means, such, for example, as the bolts 20 and nuts 21 thereon which serve to clamp the plates securely against opposite sides of the device 105 in spaced relation with the expansible portions of the diaphragms. There are thus formed between plates 18 and 19 and the adjacent diaphragms, closed recesses which are utilized as moulds for forming the sup- 110

porting abutments or surfaces for the diaphragms. To this end each plate is provided with an opening 22 through which the material to form the abutment is introduced in a fluid state. Such material is preferably one of the common metal alloys having a low melting point, although of course other substances may be employed for this purpose. This fluid material for forming the supporting abutment is introduced with the diaphragms expanded to the extreme or limiting position under which they are intended to operate, as shown in Figure 2, and the subsequent setting or hardening of the material provides a rigid body having a surface adjacent the corresponding diaphragm which corresponds exactly with the shape of the latter in expanded position and is coextensive therewith, so that the diaphragm is effectively supported over its entire surface and in its natural shape.

Before the mould recesses are filled, there is preferably introduced through a central opening 23 in supporting plate 18 a core piece 24 which is withdrawn after the casting operation to leave an opening 25 in the casting through which may be introduced for contact with the diaphragm the element connecting the latter with the apparatus to be actuated. Also, coupling member 15 is disconnected from plug 12, and a flanged bushing 26 is introduced through an opening in supporting plate 19 provided to receive coupling member 15 and is fitted about plug 12 to serve as a core providing clearance space between the cast metal and the plug 12 and coupling 15 forming the stem of the device. After the metal is poured into this mould sleeve 26 is removed and coupling member 15 reconnected. Preferably the surfaces of the diaphragms and of the sleeve 26 are coated with a film of any suitable substance, such, for example, as petrolatum to prevent adhesion of the cast metal thereto.

The supporting bodies thus formed, together with the plates 18 and 19 backing the same, serve to provide abutment surfaces substantially coextensive with the diaphragms and corresponding precisely in shape with the latter in their extreme positions of expansion, so that the diaphragms are effectively backed up and supported by a substantially rigid surface of the character described which prevents excessive expansion and possible distortion and injury of the diaphragms when subjected to pressures greater than those for which the device is designed.

The construction employed is simple, practical and effective in character and readily and economically applied to the present and other types of diaphragms and

effectively protects the device against inadvertent injury in operation and maintains it in condition for affording accurate results.

I claim as my invention:

1. In a device of the character described, the combination with a pressure-responsive diaphragm comprising opposed flexible walls and a peripheral wall, of a pair of plates disposed on opposite sides of the diaphragm and interconnected outside the confines thereof to assume a definite position relatively to the diaphragm, and means between the said plates and the said flexible walls, defining surfaces abutting with the flexible walls over substantially the entire surface thereof when the latter are in a definite expanded condition, said means consisting of material cast into the space between the plates and the said flexible walls while the latter are in expanded condition.

2. In a device of the character described, the combination with a support, a pressure responsive diaphragm having flexible walls one of which is imperforate and the other provided with an opening having its edges secured to said support, and a laterally projecting rim on said diaphragm, of a pair of plates of greater diameter than said diaphragm having their projecting peripheries secured together to support said plates on opposite sides of said rim, said plates having abutment surfaces for limiting the expansive movement of said diaphragm walls.

3. In a device of the character described, the combination with a pressure responsive device comprising a diaphragm having a laterally projecting substantially rigid peripheral portion and a flexible expandable central portion, of a plate supported on the peripheral portion of said diaphragm across and in spaced relation with said central expandable portion thereof and a body of supporting material cast in the mould formed between said plate and diaphragm in an expanded position of the latter to provide an abutment surface conforming in shape to the diaphragm in said expanded position for limiting the movement thereof.

4. In a device of the character described, the combination with a pressure responsive receptacle having opposing flexible walls expandable by pressure in the receptacle, of plates secured to said receptacle on opposite sides thereof in spaced relation with said walls by means connecting the plates together outside the periphery of the receptacle, and supporting bodies cast between each plate and the adjacent flexible wall in an expanded position of the latter for limiting the expansive movement thereof.

HARRY Y. NORWOOD.
